UNITED STATES PATENT OFFICE.

JOHN HAYS HAMMOND, JR., OF GLOUCESTER, MASSACHUSETTS.

SYSTEM OF ETHER WAVE CONTROL.

Original application filed December 27, 1910, Serial No. 599,625. Renewed September 29, 1919, Serial No. 327,268. Patent No. 1,339,927, dated May 11, 1920. Divided and this application filed April 10, 1920, Serial No. 372,742. Renewed July 11, 1922. Serial No. 574,286.

To all whom it may concern:

Be it known that I, JOHN HAYS HAMMOND, Jr., a citizen of the United States, residing at Gloucester, in the county of Essex, State of Massachusetts, have invented certain new and useful Improvements in Systems of Ether-Wave Control, of which the following is a specification, this application being a division of my application Serial No. 599,625, filed December 27, 1910, and patented May 11, 1920, No. 1,339,927.

Some of the objects of this invention are to provide an improved transmitting station for radiant energy; to provide an improved receiving station for radiant energy; to provide a transmitting station including means for continuously emitting electro-radiant waves of constant amplitude at high frequency, and a device for increasing the amplitude of certain of said waves at will in response to and in accordance with sound waves in combination with a receiving station including a telephonic receiver responsive to said waves of increased amplitude, and a signaling device unresponsive to said waves of constant amplitude but responsive to said waves of increased amplitude; and to provide other improvements as will appear hereinafter.

In the accompanying drawings, Fig. 1 is a diagrammatic view of a sending station constructed in accordance with this invention; Fig. 2 is a diagrammatic view of a receiving station constructed in accordance with this invention; and Fig. 3 is a diagrammatic view of a modified form of receiving station constructed in accordance with this invention.

Referring to the drawings, one embodiment of this invention includes a sending station comprising a high frequency current generator, or other suitable source of energy 1. This generator 1 is included in a "primary" circuit which comprises in series also a microphone 2 suitable for use with high tension currents, a non-inductive resistance 3, an inductance 4 and an arc 5. In a circuit shunted across the arc 5 is a suitable condenser 6 and the primary 7 of a transformer whose secondary 8 is connected with the aerial 9, whereby rapidly oscillating undamped waves may be emitted.

The receiving station is likewise provided with a suitable aerial 10, and with a coil 11

which is connected in series with a rectifying detector 12. Shunted across said detector is a telephone receiver 14 and a vibrating relay 15, adapted to be cut in or out of circuit by means of a suitable switch 16. A local circuit including a suitable source of energy as the battery 17 is normally closed through a suitable contact device 18 such as a platinum point attached to the diaphragm of said vibrating relay. In this circuit is included, furthermore, a relay 19, such as the well known Morse relay, in circuit with the battery 17, and a condenser 20 is shunted across said circuit. The relay 19 has its armature 21 normally attracted and controls a normally open second local or operating circuit, comprising a suitable source of energy as the battery 22 and also suitable apparatus 23 responsive to the current flowing in the operating circuit when the same is closed upon the release of the armature 21 of the relay 19. The apparatus 23 is shown as an electric alarm bell for the sake of simplicity; but it is understood that other electrically controlled apparatus may be substituted for the said bell 23, and may be in turn employed to control or operate other electrical or mechanical apparatus.

Figure 3 designates another form of receiving station, embodying a different kind of vibrating relay and contact device. In this construction the vibrating relay 15 is replaced by a similar device 24, which differs from that first described in that it has attached to its diaphragm a rod 25 of any suitable material. The end of this rod projects into the spout 26 of a mercury reservoir 27 in such a manner as to leave the spout normally open and to close the passage and to interrupt the flow of mercury through the spout only when the diaphragm of the relay 24 and the rod 25 vibrates. The falling stream of mercury 28 impinges against a metal plate 29, and then flows into a receptacle 30 from which it is pumped back into the mercury reservoir 27 by a pump 31. The terminals of a local circuit are respectively connected to the mercury in the mercury reservoir 27 and to the metal plate 29. This local circuit includes also a suitable source of energy 17, a condenser 20 in shunt circuit, and a relay 19, the armature 21 of which, when released, closes a second normally open local circuit and actuates a bell

23 or other suitable device, as before described.

In the operation of this system when the human voice or other sound producing means 5 actuates the diaphragm of the microphone 2, located at the sending station, there will be a corresponding change in certain characteristics of the oscillatory waves propagated from the aerial of the sending station. These oscillatory waves are received 10 by the aerial 10 of the receiving station. So long as the microphone 2 is at rest the train of waves emitted from the aerial 9 will be of a constant and undamped character; 15 and, because of their high frequency of oscillation, the currents induced by them pass through the rectifying detector 12 in a series of rapid impulses of uniform direction and intensity.

20 Owing to the inertia of the diaphragms of the telephone receivers 14 and the relays 15 and 24, these extremely rapid impulses of rectified current do not cause any appreciable vibration of the diaphragms, and 25 consequently no sound will be heard in the telephone receivers 14. While the effect of these extremely rapid and weak impulses upon the diaphragms of the relays 15 and 24 may be substantially the same as that 30 which would be produced by a practically steady but slight pull upon these diaphragms, this effect is not sufficient to open the contact device 18 of the relay 15 of Fig. 2, and has no tendency to close the spout 26 of 35 Fig. 3. But when the diaphragm of the microphone 2 is actuated by sound waves, such for instance as by the sound waves of the human voice, variations in accordance with the sound waves are produced in the 40 amplitude or intensity of the oscillations transmitted by the sending station and these cause corresponding variations in the amplitude or intensity of the resultant impulses which act upon the diaphragms of 45 the receiving station and consequently these diaphragms are vibrated in accordance with the sound waves thus transmitted from the sending station and corresponding sounds may be heard in the receiving telephones 50 14. This vibration of the diaphragm of the relay 15 of the system shown in Fig. 2 causes a rapid and repeated opening and closing of the contact device 18 and a corresponding rapid and repeated opening and 55 closing of the circuit through the battery 17 which causes the release of the armature 21 of the relay 19 and a consequent closing of the circuit through the battery 22 and electric bell 23 or other device.

60 When the receiving system shown in Fig. 3 is used in connection with the transmission system shown in Fig. 1, the operation is similar to that just described in connection with Fig. 2. When the microphone 2 is at rest, the diaphragm of the relay 24

is acted upon as hereinbefore described, by a series of rapid weak impulses of uniform direction, but on account of the weakness and high frequency of these impulses and the inertia of the diaphragm, the diaphragm 70 is practically unaffected and is permitted to remain in such a position as to leave the outlet through the spout 26 normally open, thus permitting a steady stream of mercury to flow downwardly through the spout and 75 to impinge against the inclined metal plate 29, thus maintaining the circuit through the battery 17 normally closed. But when the microphone 2 is acted upon by sound waves, the amplitude or intensity of the electro-radiant oscillations emitted by the aerial 80 9 is varied in accordance with the sound waves and the amplitude of the impulses received and acting upon the diaphragm of the relay 24 of the receiving station is 85 accordingly varied and thus causes the diaphragm to vibrate and to vibrate the rod 25 which then alternately closes and opens the passage through the spout 26 of the mercury reservoir, and alternately closes and 90 opens the passage through the spout. The stream of mercury 28, which normally flows without interruption, is thus broken into a series of drops by the vibrations of the rod 25. The result is that the first local circuit 95 is broken, with the result that the second local circuit is closed and the bell 23 or other mechanism is operated, as before described.

It will be understood that many changes and modifications within the knowledge of those skilled in the art may be made in the application of the system and improvements herein disclosed. It is obvious of course that any other form of electrically controlled mechanism may be substituted for the said electric bell, and that by employing suitable apparatus any number of mechanical movements may be controlled as desired, through the agency of sound-waves 105 and at any desired distance from the sending station.

Having thus fully described my invention, I claim:

1. The combination with a transmitting station for continuously emitting waves of constant amplitude and a device for increasing the amplitude of certain of the waves at will, of a receiving station including a local circuit, circuit controlling means therefore unresponsive to currents set up by said waves of constant amplitude but responsive to currents set up by said waves of increased amplitude, and signaling mechanism controlled by said circuit. 115

2. The combination with a transmitting station for continuously emitting waves of constant amplitude and a telephonic device for increasing the amplitude of certain of the waves at will in response to and in ac- 120 125 130

cordance with audible sound waves, of a receiving station including a local circuit, circuit controlling means therefor unresponsive to currents set up by said waves of constant amplitude but responsive to currents set up by said waves of increased amplitude, and signaling mechanism controlled by said circuit.

3. The combination with a transmitting station for continuously emitting waves of constant amplitude, and a device for increasing the amplitude of certain of the waves at will in response to and in accordance with sound waves, of a receiving station including a local circuit, circuit controlling means therefor unresponsive to currents set up by said waves of constant amplitude but responsive to currents set up by said waves of increased amplitude, and signaling mechanism controlled by said circuit.

4. The combination with a transmitting station for continuously emitting waves of constant amplitude, and a device for increasing the amplitude of certain of said waves at will in response to and in accordance with sound waves, of a receiving station including a local circuit, circuit controlling means therefor including a relay having a vibratory diaphragm unresponsive to currents set up by said waves of constant amplitude but responsive to currents set up by waves of increased amplitude, and signaling mechanism controlled by said circuit.

5. The combination with a transmitting station for continuously emitting waves of constant amplitude, and a telephonic device for increasing the amplitude of certain of the waves at will in response to and in accordance with sound waves, of a receiving station including a local circuit, a source of electrical energy arranged to energize said local circuit, and circuit controlling means for said local circuit including a vibratory relay having a vibratory diaphragm normally closing said local circuit, and a sig-

naling mechanism controlled by said local circuit.

6. A receiving system for radiant energy, comprising a circuit responsive to high frequency radiant oscillations of substantially constant amplitude, a telephonic receiver controlled by said circuit and arranged to be actuated by and in accordance with variations corresponding to sound waves in the amplitude of the currents set up by the said waves of constant amplitude in said circuit, a second circuit, controlling means for said second circuit controlled by said first-mentioned circuit and unresponsive to currents set up in said first-mentioned circuit by said electro-radiant oscillations of constant amplitude but responsive to currents set up in said first-mentioned circuit as the result of said variations, and signaling mechanism controlled by said second-mentioned circuit.

7. The combination with a transmitting station for emitting continuous waves, including telephone means for varying the amplitude of the waves, of a receiving station tuned to respond to the waves and including a local circuit, electromagnetic means included in the local circuit unresponsive to waves of constant amplitude but responsive to waves of different amplitude to produce a signal.

8. In a system of communication by radiant energy, marginal means constructed to respond to variations in amplitude of the radiant energy to produce a definite signal.

9. In a system of communication by radiant energy, the combination with a transmitter for emitting waves of constant amplitude including telephonic means for changing their amplitude, of a receiving station including a marginal device constructed to respond only to waves of one amplitude.

Signed at Gloucester, in the county of Essex and State of Massachusetts this 9th day of April, A. D. 1920.

JOHN HAYS HAMMOND, JR.
